(57) **CLAIM**

The ornamental design for a tiered riser rack, as shown and described.

DESCRIPTION

This patent contains at least one drawing/photograph executed in color. Copies of this patent with colored drawing(s)/photograph(s) will be provided by the Office upon request and payment of the necessary fee.

FIG. 1 is a front, top perspective view of a tiered riser rack showing my new design.

FIG. 2 is a front, bottom perspective view thereof.

FIG. 3 is a front elevational view thereof.

FIG. 4 is a rear elevational view thereof.

FIG. 5 is a top plan view thereof.

FIG. 6 is a bottom plan view thereof.

FIG. 7 is a left-side elevational view thereof; and,

FIG. 8 is a right-side elevational view thereof.

**1 Claim, 8 Drawing Sheets
(8 of 8 Drawing Sheet(s) Filed in Color)**
